UNITED STATES PATENT OFFICE.

CHARLES GILLINGS AND RICHARD MERCER, OF LIVERPOOL, ENGLAND, ASSIGNEES,
BY MESNE ASSIGNMENTS, TO AUTOMATIC ELECTRIC INC., OF CHICAGO, ILLINOIS,
A CORPORATION OF DELAWARE.

AUTOMATIC TELEPHONE SYSTEM.

Application filed October 12, 1921. Serial No. 507,365.

To all whom it may concern:

Be it known that we, CHARLES GILLINGS and RICHARD MERCER, both subjects of the King of Great Britain and Ireland, and both residents of Liverpool, England, have invented certain new and useful Improvements in Automatic Telephone Systems, of which the following is a specification.

The present invention relates to improvements in or relating to measured service telephone systems and more particularly relates to an arrangement for enabling connections to be charged for at varying rates. It has already been proposed to vary the charge according to the junction line taken into use, but obviously this system is only truly applicable where each exchange has direct access to every other exchange in the system and it does not therefore render possible the charging of varying rates where exchanges are in serial relationship. We have proposed in our British Patent Number 122,747 in such cases, to make a charge equal to the sum of the rates of the trunk lines taken into use.

It has also been proposed in telephone systems employing registering mechanism for controlling the extension of a circuit to a called line to vary the period for which one unit of charge is made in accordance with the setting of the registering mechanism for the first digit of a called party's number.

It is the object of the present invention to provide arrangements whereby the charges between any two exchanges in an area may be assessed entirely independently of the route taken, irrespective of whether the call is set up direct or through one or more intermediate exchanges, and in the case of automatic telephone systems, irrespective of the number of digits which determine the exchange in which the connection is finally set up. Consequently, it is possible for the traffic department to fix the charging rate according to the geographical distance between exchanges without reference to the actual lay out of a system.

According to the present invention, this is effected by providing a selecting device which is adapted to select the charge to be

made for a given connection as determined jointly by the exchange at which the call originates and the exchange at which the connection is finally established to the wanted party, for instance, a device may be permanently associated with the originating exchange and may be operated in accordance with certain defined characteristics of the destination exchange or similarly the device may be located at the destination exchange and operated in accordance with certain defined characteristics of the originating exchange.

The invention will be better understood by referring to the accompanying drawings in which Figures 1, 2 and 3 illustrate one example of carrying the invention into effect where the call is routed through a number of exchanges in serial relationship. Figure 4 shows a construction applicable where the charging rate may be determined by dialling one more digit additional to that determining the first trunk line over which the call is to be set up. Figure 5 shows a diagrammatic lay out of a system embracing 17 exchanges in which the charging rate is determined in accordance with the distance.

Referring to Figures 1, 2 and 3, it will be assumed that a subscriber at substation A desires to set up a connection with a subscriber in the exchange in which the connector H (Figure 3) is located. For convenience, referring to Figure 5, it will be assumed that the subscriber A has his line connected to exchange Number 1, and that the connector H is located in exchange Number 17, so that the call must be routed through an intermediate exchange 13. The connection would be set up in the usual way, the line switch C automatically operating on the subscriber at substation A lifting his receiver to find an idle selector which it will be assumed is the selector D. The selector D therefore responds to the first digit dialled and subsequently commences to rotate automatically in search of an idle trunk line leading to the intermediate exchange 13. It will be assumed that the lines 21 and 22 are the conductors of the first trunk line which is idle. At the outgoing end of this trunk line, is allocated a repeater E which is adapted to

repeat the subsequent impulses dialled by the subscriber. At the other end of the trunk lines 21 and 22, is a selector F which is substantially identical in construction with the selector D previously mentioned. This selector responds to the first set of impulses repeated by repeater E to bring its wipers to the level in which the trunk lines leading to exchange Number 17 are located. It will be assumed that the lines 23 and 24 are the conductors of the first trunk line which is found idle. At the outgoing end of this trunk line is a repeater G which functions similarly to the repeater E, while at the other end of the trunk line is located a selector K which responds to the next series of impulses, so that its wipers come opposite the level of a group of connectors in the contact banks of which is located the line of the party required. It will be assumed that the connector H is the first idle line which responds to the last two digits to establish connection with the line of the party required.

Before proceeding with the description of the metering, it will be well to point out that when the repeaters E and G are taken into use, the release relays 26 and 27 are operated in the usual way, and at their armatures 28 and 29 complete a circuit for the polarizing windings of relays 30 and 31, the other windings of relays 30 and 31 being normally connected across the trunk lines, so that the direction of current through the other winding of relay 31 depends upon whether the back bridge relay 32 in the connector H is operated or not, while the current through the other winding of relay 30 depends upon whether the reversing relay 33 of repeater G is operated. Reversing relay 33 is identical in operation with the reversing relay 34 of repeater E which it will be seen operates when relay 30 is energized. Now the windings of the polarized relay 30 and 31 are so arranged that the relay will not energize if each winding is excited separately or if the two windings are excited together, but in opposition to each other. When however, the two windings assist, the relay immediately energizes so that the relay 31 responds on the energization of the back bridge relay 32. Relay 33 then energizes and reverses current over the trunk conductors 21 and 22 so that relay 30 energizes followed by the energization of relay 34. This operation as is well known, takes place as soon as the wanted subscriber replies, and does not take place if the wanted subscriber does not reply or if the call should be made through a connector in which the back bridge relay does not reverse the current, that is to say, a connector which is only accessible to stations to which a call is not to be charged for.

On the completion of the dialling, when

it is once ascertained that the subscriber's line is idle, the wiper relay 35 operates and is locked operated in the usual manner. Armature 36 is then attracted completing a circuit for relay 37 as follows:—Earth, working contact of armature 36, armature 38 and its resting contact, resistance 39, winding of relay 37 to battery. The resistance 39 is such that the relay 37 will only be partially energized, sufficient to bring its armature 40 into contact with its working contact, armatures 41, 42 and 43 not being operated at this time. Armature 40 is connected to a common lead to which earth is connected momentarily once per revolution of a shaft carrying the cams 44, 45, 46. On the instant that earth is connected as described, to the common lead by means of the cam 44, a direct energizing circuit is provided for relay 37 which immediately pulls up the other armatures 41, 42 and 43. At armature 41 a locking circuit is provided through the back contact of armature 47, while at armature 43, a circuit is closed to a common lead 48 to which booster battery is connected in cycles of impulses by means of the cam 46 operating on the springs 49. The booster impulses as will be seen are connected to the lower talking conductor on the side which has direct connection to the intermediate exchange No. 13. The cam 46 being located in exchange No. 17 is adapted to send out 17 impulses over the lower talking conductor which, by referring to repeater G, it will be noted are adapted to cause the energization of magnet 50 of a step by step switch S individual to the repeater, the magnet 50 responding to booster impulses to advance the wipers 51 and 52 of the switch S to the 17th contact, while at the same time at its armature 53, it repeats the booster impulses over the lower talking conductor 22 thereby causing the energization of the magnet 54 of a step by step switch Q individual to the repeater E. Consequently, the wipers 55 and 56 of this switch are stepped to the 17th contacts 57 and 58 respectively. The magnet 54 also repeats booster impulses over the lower talking conductor at its armature 59, but these are of no effect as the repeater E is located at the originating exchange.

It will be understood that the exchanges are given arbitrary numbers, independent entirely of the numbering scheme adopted for dialling purposes, and by arranging for the transmission of 17 impulses over the trunk lines back to the originating exchange the switch Q serves to determine at the originating exchange, the exchange where the connection has finally been established and therefore serves as a means for selecting the charge to be made in any particular case.

Referring to Figure 5, the dotted circles drawn with exchange No. 1 as a centre, serve

to determine the successive rates of charge, within the smaller circle the charges will be at unit rate, within the second circle the charges will be at double unit rate, within the third circle, the charge will be three times unit rate and within the fourth circle will be four times unit rate.

It will be noted that a call to exchange No. 17 from exchange No. 1 should be charged at 3 times unit rate, and it will be noted that the 17th contact 57 of which Q is connected to a common lead 59 over which three impulses are transmitted during one revolution of the shaft carrying the cams 60-65 inclusive. If the exchange No. 17 had been located in either the second or fourth circles, all that would have been necessary to vary the charge would be to arrange that the contact 57 instead of being connected to lead 59 would have been connected to lead 66 or lead 67 respectively. Consequently, to vary the charge for any exchange or to make any alteration in the charging rates, all that is necessary is to vary the connections to the contacts wiped over by wiper 55. After the 17 impulses have been transmitted over the lower talking conductor by the cam 46, the cam 45 operates the springs 68 so as to connect earth to the common lead 69, and thereby cause the energization of stop relay 70. This circuit may be traced as follows:—Earth, contact springs 68, common lead 69, armature 42 and its working contact, winding of relay 70 to battery. Relay 70 energizes and establishes a locking circuit for itself at armature 38 and at armatures 47 and 38 opens the locking circuit of relay 37 which deenergizes and is unable to re-energize during the connection.

The operation so far described has simply served to indicate the destination exchange at the originating exchange, but no charge has yet been made for a connection, this of course not taking place until the wanted subscriber replies. When this happens, as is well known, the back bridge relay 32 operates and reverses the direction of current flowing over the trunk conductors 23 and 24 as previously described, so that the relay 31 and subsequently relay 30 energize.

The energization of relay 31 is identical with that following the energization of relay 30, but the resultant operation is without effect as this repeater is located at an intermediate exchange. The repeater E however is located at the originating exchange No. 1 where metering has to take place, and consequently, the operation following the energization of relay 30 will be described in full. On the closure of armature 71 of relay 30, a preliminary energizing circuit is closed for relay 72 as follows: Earth, armature 71 and its working contact, resistance 73, winding of relay 72, contact 58, wiper 56 to bat-

tery. The resistance 73 is sufficiently great to ensure that the relay 72 cannot operate fully but only sufficiently to bring its armature 74 into connection with its front contact. The armature 74 is connected to a common lead 75 to which earth is connected once per revolution by means of the cam 60. Assuming therefore, that earth is connected to lead 75, after armature 74 has been attracted, the relay 72 can fully energize and thereby attract its armatures 76-79; at armature 78 relay 72 establishes a locking circuit for itself, while at armature 76 a circuit is prepared for the release magnet 80. At armature 77 the release trunk conductor 81 which is normally connected through armature 82 of release relay 26 to earth on spring 83 is connected to wiper 55 and thence via contact 57 to common lead 59 and earth on springs 84. Everything is now in order for the sending of the booster impulses.

As will be seen from Figure 1, the meter M is connected to the release trunk conductor 81 through the working contact of armature 86 of the cut off relay 87 of line switch C and thence through wiper 87, bank contact 88, working contact 89 of switching relay 90 to wiper 91 and bank contact 92. The meter M is so designed that it will not operate under normal conditions, but will only operate when booster battery is connected to the release trunk conductor, so as to increase the current through it. Consequently, the cam 63 will operate the springs 84 to place booster battery on the lead 59 three times during a revolution of the cam shaft, thus operating the meter three times. Just prior to the conclusion of the revolution, the cam 61 operates its contact springs 93 to connect earth to the common lead 94 thereby completing through armature 76, the circuit of the release magnet 80. The release magnet therefore energizes, and remains energized until the wiper 56 reaches its normal position, when battery is disconnected and release magnet deenergizes as also the relay 72. Conditions are therefore restored to normal. As the release trunk conductor at the intermediate exchange No. 13 obviously has no meter connected to it, it would be appreciated that although the booster impulses are connected over it in a similar manner to that described with respect to repeater E, these will be without effect.

It will thus be appreciated, that by means of the invention, it is possible to charge for a call irrespective of the route over which the call has been set up. For instance, by reference to Figure 5, it will be noted that exchanges Numbers 1, 3, 7, 8, 11, 13 and 15 could all be charged at unit rate for subscribers connected to exchange No. 1. It will therefore be noted that the 1st, 3rd,

7th, 8th, 11th, 13th and 15th contacts are all connected to the lead 95 to which one booster impulse is connected once per revolution of the cam shaft. In exchange No. 5 13 for which a second series of dotted circles are shown in Figure 5, exchanges Nos. 1, 7, 11, 12, 13, 15, 16 and 17 are all connected to the lead 96 which is similar to the lead 95 and to which one booster impulse is 10 connected once per revolution of the cam shaft at that exchange. In view of the metering arrangements having been effectively cut out, on the release of the switches Q and S to normal, it will be appreciated that 15 the release of the connection takes place in the usual way without in any way affecting the metering arrangements.

In the special case of calls local to an exchange in which connections there will 20 necessarily be no repeaters, it would be necessary either to provide a special switch, say at the first selectors designed to respond to the booster impulses transmitted on the 25 operation of the wiper relay, or alternatively arrangements would be provided for sending a unit impulse for the release trunk conductor which in the case of a local call of course extends throughout the connection. The arrangement for effecting this is shown 30 in Figure 3. On the energization of the back bridge relay 32, when the wanted subscriber replies, a circuit is closed for relay 100 as follows:—Earth, working contact of armature 101, back contact of armature 35 102, resistance 103, relay 100 to battery. The resistance 103 is sufficiently great to prevent relay 100 fully energizing, and at this time, it only energizes sufficiently to attract its armature 104. Armature 104 is 40 connected to common lead 105 to which earth is connected once per revolution by means of the cam shaft 106, so that not until the cam 106 is in a certain position can the relay 100 fully energize. When it does so, it attracts its armatures 107—109 inclusive. At 45 its armature 109, it completes a locking circuit for itself through back contact of armature 110, armature 109 and its working contact, resistance 103, relay 100 to battery. Resistance 103 permits sufficient current to 50 pass through relay 100 to hold it energized, although not sufficient to permit it to energize. The earth on the release trunk conductor which is received through the springs controlled by armature 108 and armature 55 111 of release relay 112 is replaced by earth on the common lead 113, to which a booster impulse is connected on the operation of springs 114 by the cam 113 once per revolution. This booster impulse therefore serves 60 to operate the meter once, and is followed by the closure of the springs 116 by the cam 117, whereby earth is connected to the lead 118 which causes the energization of the 65 left hand winding of relay 119 through

armature 107. Relay 119 therefore energizes, and at its armatures 110 and 102 breaks the locking circuit of relay 100, while at armature 102, it completes a locking circuit for its right hand winding and at armature 120, an auxiliary locking circuit is connected to the release trunk conductor for its right hand winding. The duplicate locking circuit for relay 100 is provided in order to ensure that the metering is effected if either the called or the calling subscriber 70 should hang up the receiver before the metering is completed, while the dual locking circuit for relay 119 is provided to ensure that the relay cannot deenergize until both 80 subscribers have hung up their receivers, thereby preventing the metering being repeated during a call.

In Figure 4, an alternative arrangement is shown for application to automatic telephone systems in which the first digit dialled after access has been gained to a repeater is sufficient to determine the destination of a call. In order to describe this arrangement, only that part of a repeater 90 similar to E which is necessary to understand the invention is described. A 10 contact switch P is provided which is individual to the repeater and is controlled by an operating magnet 130 and a release magnet 131. The first series of impulses repeated by the line relay 132 of the repeater in addition to causing the energization of the relay 134, are adapted to cause the energization 95 of the magnet 130 in the following circuit:—Earth, armature 135, and its resting contact, armature 136 and its working contact, series relay 137, off normal springs 138 and 139, magnet 130 to battery. The magnet 130 responds to the first digit to advance the 100 wipers 140 and 141 on to the first contact. Relay 137 at its armature 142, maintains the impulse circuit through the vertical magnet 30 after the off normal springs have 105 been operated to their alternate position through the springs 143 and 139, so that the vertical magnet responds to all the impulses in the first digit transmitted after the repeaters are seized. Wipers 140 and 141 110 therefore advance accordingly and the contacts are connected in a similar manner to that described with reference to the switch Q except that it is the number of the party called instead of a special number allocated to the exchange which determines the party 115 required. As mentioned before, in certain cases, it is possible that the first digit dialled after the seizure of the repeater will be sufficient to determine the destination exchange, and therefore no further provision 120 is necessary.

It will be noted that the leads from the contacts are similar to the common leads 95, 66, 59 and 67; while 3 leads on the right hand of the switch are identical with those 125 130

leading to armature 76, armature 77 and the winding of relay 72, so that the subsequent operation of the charging arrangements is identical with that described with relation 5 to Figure 2.

Obviously, after the one set of impulses has been transmitted by a repeater, the relay 137 deenergizes and other impulses will only be effective in operating the relay 134 10 following standard practice. If it was desired to have a switch designed to respond to two digits by the repeater, this would obviously be provided but it is doubtful whether it would not prove too expensive. 15 It should be mentioned that the dotted connections to armature 79 and its working contacts are provided in order to prevent the release of the connection in case the calling subscriber should hang up before the 20 metering has been properly effected. The energization of the release relay by armature 79 effectively prevents this as will be understood.

It will be understood that the arrangements shown are only given by way of example, as obviously, several modifications could be made in the manner of carrying the invention into effect without departing from the spirit of the invention.

Having now particularly described and ascertained the nature of our said invention, and in what manner the same is to be performed,

What we claim as our invention is:

1. In a telephone system embracing a number of exchanges, means for establishing connections from one exchange to another, means in the calling exchange controlled from the called exchange for determining the charge to be made for the call, and circuit arrangements such that the exercise of the control is delayed until a plurality of series of digit impulses are transmitted to the called exchange.

2. In a telephone system embracing a number of exchanges, means for extending connections from calling lines in any exchange to a called line in any other exchange, a code interrupter in each exchange 50 which sends a code of impulses to the calling exchange whenever a call is extended thereto, means in the calling exchange responsive to said code of impulses for selecting the device for charging the proper toll for the particular connection, and a plurality of different devices in the calling exchange available for selection.

3. In a telephone system, called lines in one exchange, calling lines in a plurality of other exchanges, the calling line in each of the other exchanges being assessed a different toll to call the called line, a code interrupter in said one exchange arranged to send a definite number of impulses to any other exchange calling into said one ex-

change, and means in each of said other exchanges for assessing the required toll responsive to said impulses.

4. In a telephone system having arbitrarily established zones of calling, with 70 established rates for calls extending between zones, means for establishing connections from one zone to another direct or through a number of intervening zones, and selective means in each exchange controlled from the 75 called exchange for charging at the proper rate regardless of the number of intervening exchanges or zones.

5. A telephone system in which there are 80 a number of exchanges, and means for extending connections between exchanges, means in each exchange when called for transmitting a special series of impulses characteristic of that exchange, and means in each exchange when calling responsive to 85 the impulses from the called exchange for determining the charge to be assessed for the call.

6. A telephone system in which there are 90 a number of exchanges, and means for extending connections between exchanges, means in each exchange when called for transmitting a special series of impulses characteristic of that exchange, and means in each exchange when calling responsive to 95 the impulses from the called exchange for determining the charge to be assessed for the call, independent of the route taken by the call.

7. In a telephone system consisting of a plurality of exchanges located at varying distances from each other and requiring different rates of toll for calling between the various exchanges, means associated with each exchange for sending a definite number 105 of impulses to any exchange calling that exchange, and additional means in each exchange operating in response to the impulses received from the particular called exchange for determining the proper rate of 110 charge.

8. In a telephone system comprising a number of exchanges, means for setting up connections between lines in said exchanges, a selecting device located in the exchange in 115 which the call originates for determining the charge to be assessed for the call, said device controlled solely from the exchange in which the line called is located.

9. In a telephone system comprising a 120 plurality of exchanges, a code sending device for each exchange operating to transmit a special series of impulses indicative of that particular exchange, over any connection extended to that exchange, and a 125 selecting device in each exchange operated when that exchange is calling, which responds to the series of impulses from the called exchange to assess the charge for the call between the two exchanges. 130

10. In a zone metering telephone system, a plurality of exchanges, a selecting device in each exchange having a plurality of contact sets, one set for each of the other exchanges, means in each exchange operable when calls are received for setting the selecting devices in the exchanges where the calls originate, each selecting device being always set on the particular contact set corresponding to the called exchange, and circuit arrangements and apparatus by means of which each selecting device controls the assessing of charges against calling lines which vary in accordance with the exchanges to which the calls are extended.

11. In a zone metering telephone system, a first exchange, a plurality of other exchanges, automatic switches for connecting calling lines in any of said other exchanges with called lines in said first exchange, a device in said first exchange for transmitting a series of impulses to the calling exchange each time a call is received, the number of impulses being fixed and independent of which exchange is calling, a selecting device in each of said other exchanges adapted to respond to such series of impulses to always select a particular contact set, and circuit connections to the contacts sets in said selecting devices which vary in accordance with the exchanges in which the selecting devices are located so that calling parties in different ones of said other exchanges may be charged different amounts for calls to said first exchange.

12. In a telephone system embracing a number of exchanges, means for establishing connections from one exchange to another, means in the calling exchange determining the charge to be made for the call, and means operative responsive to the seizure of the line called for rendering the means in the calling exchange effective.

13. In a telephone system consisting of a plurality of exchanges located at varying distances from each other and requiring different rates of toll for calling between the various exchanges, a plurality of meter operating devices associated with each exchange, means also associated with each exchange for sending a definite number of impulses to any exchange calling that exchange and additional means operative in response to the impulses received from the particular called exchange for selecting a particular one of said meter operating devices to determine the proper rate of charge.

14. In a telephone system comprising a plurality of exchanges, a plurality of meter operating devices, a selecting device located in the exchange in which the call originates

for selecting one of said meter operating devices to determine the charge to be assessed for the call, said selecting device controlled solely from the exchange in which the line called is located.

15. In a telephone system comprising a plurality of exchanges, means for extending connections from the calling lines in any exchange to a called line in any other exchange, continuously operating impulse transmitters for starting, transmitting and stopping the transmission of a code of impulses to the calling exchange whenever a call is extended thereto to determine the charge to be made for the call, means operative responsive to the seizure of the line called to connect one of said impulse transmitters to cause said means to operate further at the appropriate time to also connect the other of said transmitters, and means responsive to the actuation of one of said transmitters to disconnect all of said transmitters after the charge determining impulse code has been sent.

16. In a telephone system embracing a plurality of exchanges, means for establishing connections from any one exchange to any other, automatic switches and pulsing elements at each exchange, impulse contacts operated by said pulsing elements having connections terminating in the banks of the said automatic switches located at their respective exchanges, other pulsing elements at each respective exchange, and means for causing one of said other pulsing elements of any exchange to transmit impulses to any other exchange calling it to operate a said automatic switch of such calling exchange to select one of said first pulsing elements to determine the charge to be made for the call.

17. In a telephone system embracing a number of exchanges, means including a connector switch for establishing connections from lines of one exchange to lines of the same or another exchange, a line switching relay and a back bridge relay in said connector, means in the calling exchange controlled by the switching relay of said connector, when the call originates in another exchange, to determine the charge to be made for the call, and other means controlled by the back bridge relay to actually register the charge when the calling and called exchange is one and the same.

Signed by me at Liverpool, England this 9th day of Sept. 1921.

CHARLES GILLINGS.
